UNITED STATES PATENT OFFICE.

ORRELL ASHTON, OF LAWRENCE, MASSACHUSETTS, ASSIGNOR, BY MESNE ASSIGNMENTS,
TO UNITED SHOE MACHINERY COMPANY, A CORPORATION OF NEW JERSEY.

MACHINE FOR INSERTING SCREW-THREADED FASTENINGS.

No. 920,241.

Specification of Letters Patent.

Patented May 4, 1909.

Application filed August 19, 1898. Serial No. 688,992.

To all whom it may concern:

Be it known that I, ORRELL ASHTON, of Lawrence, county of Essex, State of Massachusetts, have invented an Improvement in 5 Machines for Inserting Screw-Threaded Fastenings, of which the following description, in connection with the accompanying drawings, is a specification, like characters on the drawings representing like 10 parts.

This invention has for its object to improve and simplify machines of the class represented in United States Letters Patent No. 490,621, dated Jan. 24, 1893.

15 The patent referred to shows a wire feeding mechanism composed of a constantly rotating wire-carrying spindle provided with grippers which grasp the wire to feed and insert the same into the stock sustained 20 by a horn, said grippers being operated through a sleeve actuated by a feed lever having a roller or other stud which is acted upon by a face-cam carried by a continuously operating shaft, and when the feed of 25 the wire is to be stopped, the feed lever having the roller or other stud is locked in such position that the cam in its rotation while meeting the roller will not actuate the lever for a distance sufficient to effect the 30 feeding of the wire, and consequently the feed of the wire is temporarily suspended without, however, stopping the rotation of the spindle carrying said grippers. The 35 lever and roller of the wire feeding mechanism are under the control of a knee lever which is moved in one direction by the operator when it is desired to arrest the feeding movement of the wire, and in an opposite direction when it is desired that the wire 40 feeding mechanism shall act to feed the wire, the wire during the feeding action being thrust into the stock and thereafter cut off for the production of a fastening. In the machine of said patent the length 45 of wire fed through the throat by the wire feeding mechanism varies according to the thickness of the stock then on the horn and to receive a fastening, and the extent to which the wire is fed for the formation 50 of a first fastening after starting the wire feeding mechanism is determined, while the machine is running, by the roller of said lever meeting said face cam, the point of contact varying, it will be understood, according to the thickness of the

stock on the stock support. The shaft carrying said face cam and rotated continuously at very high speed forms what will be hereinafter designated as a continuously moving actuator for the wire feeding mechanism. 60

When the operator desires to start the feeding of the wire he moves the knee lever to release the lever of the wire feeding mechanism that it may start and the roller 65 thereof contact with said cam, but owing to the fact that said lever is released at the will of the operator, it happens that the roller of said lever in practice hardly ever meets exactly the proper point on said 70 rapidly moving cam or actuator to insure the feeding of the wire for a distance sufficient to produce a first fastening of a length sufficient to penetrate the stock then on the horn, and consequently the first fastening 75 is almost invariably too short and fails to unite the work properly. The reason why the fastening first formed after starting the wire feeding mechanism is usually too short is that the operator is unable to 80 determine accurately the instant at which he must move the knee lever that the roller may meet the inclined face of the rapidly moving cam at just the proper point to cause the wire feeding mechanism to grasp 85 and feed the wire for the formation of a first fastening of the right length to fully penetrate the particular thickness of stock 90 then on the horn.

I have aimed herein so to improve machines of the class referred to that the operator, preparatory to starting into operation the wire feeding mechanism and other parts, may move a manually controlled device and prepare a controlling lever to be thereafter 95 moved automatically and cause the roller of the feed lever to contact with said continuously moving actuator to start the feeding mechanism for feeding the wire, the point of contact of said roller with said actuator varying with the thickness of the stock, the contact being, however, always at 100 exactly the proper point with relation to the length of the inclined face of said actuator to insure the movement of the wire feeding mechanism, at the first feeding operation of the wire feeding mechanism, for such a distance as to insure the production 105 of a fastening of exactly the proper length to penetrate the stock then on the horn. 110

The first feeding movement having been effected, and a fastening of the proper length having been inserted in the stock, the second and other succeeding feeding movements of the wire will result in the production of fastenings which shall all be of the proper length to penetrate the stock substantially to the tip of the horn.

Through the manually controlled device 10 and the automatically controlled starting device I am enabled to obviate the formation of any short fastenings, and a fastening of the proper length may be insured for each wire feeding stroke even though the wire feeding mechanism were stopped after inserting each fastening.

In the machine described in said patent the operation of the cutters of the wire cutting mechanism for severing the wire close to the stock after the same has been inserted to form a fastening, does not stop when the operation of the wire feeding mechanism is suspended, and they hit together and become dulled, and also in said patented machine 25 as made and put on the market, the horn is depressed automatically preparatory to each feeding movement of the stock over the horn, but when the wire feeding mechanism is stopped the horn is left in contact with the underside of and clamping the stock so 30 that before removing the stock from the horn the operator has to put his foot upon a treadle and further depress the horn sufficiently to enable the stock to be removed.

35 I have herein made provision whereby the operation of the wire cutting mechanism may be entirely suspended whenever the action of the wire feeding mechanism is suspended, and whereby when the operation of 40 the wire feeding mechanism is suspended the horn will be lowered and locked in a depressed position with the tip of the horn occupying a position in which the stock is unclamped ready to be removed from the 45 horn and in which other stock may be applied to said horn.

To effect my invention in one form, the best form now known to me, I have in the machine herein illustrated and described 50 provided at one side of the column mechanical devices which I designate as a lock that may be set through a manually controlled device, and be thereafter retained and moved automatically in defined time and order to cause the wire feeding mechanism to be 55 started and moved unerringly at its first stroke for the production of a fastening long enough to penetrate the stock to the tip of the horn.

60 Figure 1, in left hand elevation, shows a sufficient portion of a machine for inserting wire, which may be screw-threaded, into boots or shoes or other material resting upon the horn, with my improvements 65 added, to enable my invention to be under-

stood; Figs. 1^a and 1^b are respectively a sectional detail and lower end views of the wire-carrying spindle, gripper carrier, sleeve and grippers; Fig. 2 shows the lower end of the machine shown in Fig. 1, a small portion of the column being broken out to save space on the drawing; Fig. 3 is an enlarged detail view, partly in section, of the lock and some of the parts co-operating therewith, to be described; Fig. 4 is a 75 similar view to Fig. 3, but with the lever c²¹ shown in a different position; Fig. 5 is a detail looking at the left of Fig. 3; Fig. 6 is an enlarged section looking to the left of the section line x, Fig. 1; Fig. 7 is a detail 80 of the wedge for moving the stop co-operating with the measuring device of the feed lever; Fig. 8 shows in two views the movable heel and part of its sustaining lever instrumental in actuating the wire-cutting 85 mechanism; Fig. 8^a, a detail showing the stop for suspending the operation of the feed lever and part of its carrying rod; Fig. 9 is an enlarged detail showing the 90 lock and connected parts applied to the column looking at the same in the direction of the arrow 2, Fig. 1; Fig. 10 is a detail at the right-hand side of the head, chiefly to show the feed lever D¹⁴, its attached measuring device, the cam or actuator for moving said lever, and the stop, the latter holding the feed lever and its roller in their inoperative relation with said cam; Fig. 11 is a detail 95 showing in face view the cutting means used to cut the wire into fastening lengths, and Fig. 12, a detail showing the locking bar 100 detached.

The column A, supporting the head A^x, the rotating wire-carrying spindle A¹⁰, the sleeve F embraced by the yoke D¹⁰, the feed 105 lever D¹⁴, pivoted at D¹⁵, said lever having a roller or other stud D¹⁶, shown by dotted lines, Fig. 1, which is acted upon by the face cam D¹⁷, fast on the shaft B¹⁴, the spring 110 actuated toothed box 104, the rod 100 actuated by said box to move said roller toward said cam, the worm toothed gear d⁷⁰ on said shaft, it being engaged by a worm on said rotating spindle, the latter deriving its motion from a belt extending over a pulley A⁹, 115 fast thereon; the cam B¹³ fast on said shaft B¹⁴, and having two toes C¹ and C² to actuate at proper times the wire-cutting mechanism to be described; the horn depressing lever B⁹ pivoted at B¹⁵, and slotted for the 120 reception of a stud; the cutter actuating lever C, the spring 112 surrounding the rod 113, and normally keeping said lever elevated; the toothed gear d⁹, see Fig. 1, fast to the cam wheel B¹³ and engaging a second 125 like toothed wheel d⁸ on the shaft d^{7x}; the lever e⁶ instrumental in actuating the feeding device for feeding the shoe over the horn; the link C⁵ connected with the lever C, which is moved when the wire-cutting 130

mechanism is to be actuated, said link operating the cutter-carriers 121 and 123, the measuring device or leg G³ having the nut or projection 40; the grippers b' pivoted upon a gripper carrier d, the rollers b³, carried by the sleeve F; and the horn B, its attached horn shaft B', the arm G attached to said horn and carrying a measuring rod G', see Fig. 6, it coöperating with the measuring leg G³; the fast and loose pulleys A³, A⁴, shown in Fig. 2, the sliding cam A⁶ coöperating with the wedge A⁶⁰ and controlled by the lever A⁷ to stop and start the spindle, the shaft B¹⁴, and its actuating cams, the horn extension B² having the lifting spring B⁴, the lever B³ to which said extension is connected, and the nose or foot plate f, are and may be all substantially as represented in said Patent No. 490,621, it being understood that the cutting mechanism is actuated by teeth at the front end of the hollow shaft C⁹, as fully represented in said patent, so that said parts need not be herein further described.

25 The invention to be herein described is not limited to the exact shape shown for the measuring leg G³ or its nut or projection, so long as it moves with the feed lever D¹⁴.

The rod d⁶ operatively connected with 30 the horn and having at its upper end a bar d⁵, shown as toothed, and the engaging device d shown as a pawl of a carrier d² for engaging said bar and lifting the same to depress the horn, and which when lowered 35 may slide freely over said rack or bar to adapt it to depress the horn uniformly from a variable base line, namely, the underside of the stock, preparatory to feeding the stock over the horn, are and may be all as 40 usual and as common to United States Letters Patent No. 265,227, dated September 26, 1882. When a fastening is being inserted, the tip of the horn is held by spring B⁴ against the stock to clamp it against the 45 nose or foot plate f.

As I have illustrated my invention, the carrier d² has connected with it, by a screw B²⁵, see Figs. 3 and 4, a stirrup B²⁴, having at its upper end a sleeve B²³, through which is extended loosely a continuously moving rod B²², united in an adjustable manner by a suitable bolt B²¹ to the horn depressing lever B⁹, see Fig. 6, the bolt entering a slot in said lever, said lever being operated continuously by or through a cam groove 121, cut at the inner face of the continuously moving actuator B¹³ for the horn-depressing and the wire-cutting mechanisms, said cam groove having, as represented, two throw points 120. The rod B²² for moving the carrier d² is loosely connected therewith, whereas the rod in Patent No. 265,227, is fixed to said carrier. To effect this loose connection the rod B²² is provided with a collar B³⁰, see Figs. 1 and 9, and is sur-

rounded below said collar with a spring B³¹, the lower end of which rests upon the sleeve B²³, the extreme end of said rod extended loosely through said sleeve having applied to it a nut or shoulder B³². As the 70 rod B²² is depressed, the spring B³¹ acting on the carrier depresses the latter in a yielding manner, causing the pawl d to slide or click over the teeth of the rack or bar d⁵ when the stock is of increasing thickness to thereby effect the reengagement of 75 said pawl or engaging device with said rack or bar at a suitable point thereon to again depress the horn at the next rise of the carrier for a defined distance from the under 80 side of the stock. The rod B²², collar B³⁰, spring B³¹, and nut B³² constitute a yielding actuator for the carrier. The nut lifts the carrier positively to depress the horn that the stock may be fed, and also that the 85 stock may be removed, yet when the horn is locked in its lowered position for the removal of the stock, as will be described, the spring B³¹ permits the rod, which is moved continuously, to descend in the sleeve B²³ 90 without moving the carrier.

The carrier has connected to it near its upper end by pins d¹⁸ a locking-bar clamp or extension d¹⁹ composed preferably of steel. This extension is further secured to 95 the carrier by a screw d¹⁵, the latter entering a hole in a finger d¹⁶ shaped at its lower end, see Figs. 3 and 4, to form a cam 20, the screw d¹⁵ fastening the finger to the carrier. The rack or bar d⁵ and the carrier 100 d² are movable in a guideway of the column a, and between said column and a cap-plate D²⁰ forming part of a guide frame D²⁹ secured to the column by bolts D²¹ extended through holes in said cap-plate, see 105 Figs. 3, 4 and 5, for the reception of a locking device 60 having at one side a roller or other stud 61 that is struck at each descent of the carrier d² by the cam face 20 of the finger d¹⁶ movable therewith, a 110 spring 62 bearing on one end of said locking device, Figs. 3 and 4, acting normally to press the roller stud 61 toward said finger. The lock frame has a hub 56, a guiding boss 50, and sustains a screw stud 115 c²². The screw stud c²² receives and forms the fulcrum for a controlling lever c²¹ having in one of its arms a stud c²⁰ that enters loosely a slot, see Fig. 12, in the side of a locking bar d²⁰, that is sustained at its lower 120 side by and may be slid on the upper edge or shoulder d¹³ of the plate D²⁰. The other arm of the controlling lever has a passageway made therethrough, the lower part of which is shown as having a concaved seat 125 46. The opposite end of said passageway is screw threaded and receives a turret 42 containing a spiral spring 47. The passageway receives through it, before the turret is put in place, the lower end of a rod 130

43 shown as having a head 45 of spherical shape at its lower side. This rod 43 has applied to it a block 48 held in adjusted position thereon by a set screw 49, and said rod is then extended through the guiding boss 50 where it is surrounded by a spring 51, the lower end of which is sustained by a collar 52 fastened to said rod by a set screw, as shown in Fig. 1.

10 The lower end of the rod 43, see Fig. 2, is connected with a treadle 44 pivoted at d^{10} . The rod 43 constitutes one suitable form of what I herein designate manually controlled means which may be moved by the operator 15 prior to starting the wire feeding mechanism to prepare the controlling lever for thereafter starting automatically the wire feeding mechanism at just the proper time to insure such a length of stroke for the feeding lever of the wire feeding mechanism as 20 will cause the production of the first fastening to be made, of a length to fully penetrate the stock then on the horn.

The split end of the controlling lever has 25 clamped therein a stud c^{23} that enters loosely a split hub 22 of an arm 22^x that is confined by a clamp screw 23 to a rod 24 having at its upper end a wedge 25, see Figs. 1 and 7, said rod being guided at its 30 lower end in the hub 56. This wedge is shown as split at its upper end to inclose a 35 slideable stop rod 34, see Figs. 7 and 8^a, carrying at its end a stop 35 that takes the place of the pivoted block 27 having a hole, shown in said Patent #490,621, as coöperating with the measuring leg. The rod 34 has fastened to one of its ends by a set screw 39 a split hub 40^x having an inclined or beveled face next the inclined side of the 40 wedge 25, said rod being surrounded at the opposite side of said wedge by an anti-friction or steel washer 38, and between said stop 35 and the part of the framework which serves as a guide for said rod, the latter 45 is surrounded by a spring 36.

When the wedge is pulled out as in Fig. 7, from between the hub 40^x and the washer, the spring 36 causes the stop to pass under the nut or projection 40 of the measuring 50 leg G^x carried by the feed lever D¹⁴, this happening when the feed lever is at the extent of its movement derived from its continuously moving actuator, after, however, the operator has released the manually controlled rod 43 preparatory to suspending the wire feeding mechanism, it being supposed that it is desired to remove the work and apply new work to the horn. Whenever the wedge 25 is pushed automatically into 55 the space between the hub and washer through the automatic movement of the controlling lever, as will be described, the stop 35 will be withdrawn from under the nut or projection 40, thus instantly placing the 60 feed lever under the control of the rod 100

controlled by the spring box 104 that the stud of said feed lever may approach and meet said cam or actuator at a defined point, that it may be moved for just the proper distance to insure that the stroke of the wire feeding mechanism shall be of just the proper length required for the production of a fastening of the length necessary to fully penetrate the stock then on the horn. At this time the measuring rod connected with the horn and contacting with the lower end of the measuring leg serves to caliper the stock and determine the length of stroke for the wire feeding mechanism in the production of the next fastening to be thrust 80 into the work.

When the wedge 25 is in its inoperative position, Fig. 7, and the stop 35 is in position to suspend the action of the wire feeding mechanism, the lower end of hub 22 85 contacts with the hub 56, as in Figs. 1 and 3, and at other times it will be lifted from contact therewith, as will be described.

The wedge constitutes what I shall at times designate as a releasing device, which 90 when in one position enabling the wire feeding mechanism to be started automatically at exactly the proper time with relation to the cam face of the continuously moving actuator to insure the starting of the wire 95 feeding mechanism at exactly the instant necessary to feed the wire to cause the first fastening to be made to penetrate the stock then resting on the horn, and when in its other position permitting the spring 36 surrounding said rod 34 to immediately push the stop 35 under the nut or projection 40, it being understood that said nut or projection has been raised by the continuously moving actuator in actuating said feed lever 100 and the wire feeding mechanism.

The free end of the arm 22^x, see Fig. 4, extended from the hub 22 has a hole that receives loosely a rod 26, connected, see Fig. 6, at 27 with an arm 28 extended from a block having a heel 29, see Fig. 8, seated in or joined to a lever C common to said first mentioned patent, said lever actuating the connected link C⁵ and moving the cutter 110 holders, common to said patent to sever the wire at the surface of the stock after the point of the wire has been passed through the stock.

The rod 26 has a collar 54, see Figs. 1 and 9, and below said collar said rod is provided with a spring 55, which bears on said arm 22^x, the movement of said arm acting through said spring to put said heel 29 in its operative position, see dotted lines Fig. 8, so as to be struck by the toes C', C², of the continuously moving cutter actuator B¹³, but when said heel 29 is not held upwardly by said spring in its operative position then the weight of the rod 26 connected with the arm 28 carrying said heel turns said heel into 12

its full line position, Fig. 8, and dotted line position, Fig. 6, so that the action of the wire cutting mechanism is at that time suspended. The arm 28, having the heel 29, the rod 26, and hub 22 having the arm 22^x, constitute one available form of connection for suspending the operation of the wire cutting mechanism when the wire - feeding mechanism is inoperative, but this invention is not limited to the means represented, as instead I may use any equivalent means adapted to be actuated by a controlling or starting lever under the control of a manually controlled device to effect the purpose contemplated.

The wire feeding mechanism and wire cutting mechanism can be made operative only after the movement of the controlling lever c^{21} in a direction to withdraw the stop from under the nut or projection 40.

The acting end of the locking bar d^{20} , see Figs. 3, 4 and 12, is beveled at its top edge that it may more readily enter the space between the extension d^{18} of the carrier, and the bar sustaining surface or shoulder d^{13} of the lock frame D^{20} preparatory to locking the horn and suspending the operation of the wire cutting and wire feeding mechanisms, said locking bar when withdrawn from between said extension and said shoulder by the automatic movement of said controlling lever due to the action of its compressed spring 47^x, releasing the horn that it may rise under the action of the spring B^4 and clamp the stock. The spring 47^x contained in the turret 42 connected with the lever c^{21} is adapted to be acted upon by the upper end of the controlling rod 43 as the latter is raised by the treadle 44, such movement of the rod compressing said spring and storing up its energy for future use in starting automatically the controlling lever c^{21} at just the proper time to insure the starting of the wire feeding mechanism. This spring is compressed only when the wire feeding mechanism is inoperative and at rest and while the extension d^{18} of the carrier rests upon the locking bar d^{20} , the horn being then in its lowered position for the removal of work, the usual spring B^4 surrounding the horn extension B^2 being effective in holding said block or extension seated on said locking bar.

When the operator depresses the front end of the manually controlled lever or treadle preparatory to starting into operation the wire feeding and wire cutting mechanisms the block 48 is raised from its position Fig. 1, sufficiently to enable the locking device 60 under the control of said spring 62 to be immediately moved to occupy a position under said block, thus holding the rod 43 in a position to hold said spring 47^x compressed until such later time as its force is to be exerted through said controlling lever to

move the wedge 25 in a direction to withdraw the block 35 from under the nut 40, this being done automatically just prior to the time that the wire feeding mechanism is to be started to engage the wire and feed the same for the production of a first fastening. The block 35 is withdrawn from below the nut or projection 40, and immediately the lower end of the measuring leg G^2 contacts with the measuring rod G' which is moved vertically in unison with the horn, the meeting of said leg with said rod caliper the stock. This is done prior to the contact of the feed lever with the cam D^{17} , and the stock having been calipered, the cam thereafter in its movement meets at just the proper point of its inclined face the roller of the feed lever, and starts said lever that it may effect the feeding of the wire for just the proper length to insure that the first fastening to be made shall penetrate the stock to the tip of the horn. As herein provided for, this movement of the stop 35 to release the nut 40 of the measuring leg and let the wire feeding mechanism start can take place only at exactly the right time in the rotation of the cam D^{17} to enable said roller or other stud to contact unerringly with exactly that part of the face of said cam which is required to effect the feeding of the wire for a length to enable it to be forced into the stock far enough to penetrate the stock of the thickness calipered and cause the wire to substantially reach the tip of the horn so that the first fastening formed in starting the machine is not shorter than required but is of just the proper length, and in this way it is possible to start the machine in operation after suspending the wire feeding and insure the formation of a fastening of the proper length, and the means for effecting this starting of the wire-feeding mechanism forms an important feature of this invention. The nut B^{32} of the rod B^{22} at each upward stroke of said rod contacts with the stirrup B^{24} , and even when said stirrup is held up by the rod or locking bar d^{20} , the carrier and its extension d^{18} is lifted sufficiently above the shoulder d^{13} to release the locking bar so that the lever c^{21} may at such instant be moved provided the spring 47^x has been compressed as stated, and the manually controlled means is held by the locking device 60 in a position to maintain the spring 47^x compressed, the starting of said controlling lever c^{21} by the power stored up in the spring immediately restoring to operation the feed lever and the wire feeding mechanism, and the wire cutting mechanism. The operation of the wire feeding and wire cutting mechanisms will not be stopped until the operator removes his foot from the treadle controlling the manually controlled means.

Whenever the locking bar d^{20} occupies a

position between the extension d^{18} of the carrier and the shoulder d^{12} of the plate of the lock frame, then as the rod B^{22} descends the spring B^{31} , as soon as the extension meets said locking bar, is compressed, but the lever B^9 and the rod B^{22} continue to move, the nut on the rod retiring from contact with the lower end of the sleeve B^{23} of the stirrup B^{24} , and said locking bar by arresting the descent of the carrier causes it to be held in substantially its most elevated position with its pawl or engaging device d in engagement with the rack or bar d^5 , thus holding the horn in its lowered position, and during the time that said locking bar is so interposed between the extension d^{18} and the shoulder d^{12} , the spring B^4 , which acts normally to elevate the horn, exerts a pressure to clamp said locking bar d^{20} firmly and retain the lever c^{21} in its inoperative position, said clamping action being maintained throughout most of the cycle of operation of the main shaft of the machine, said clamping being, however, intermittently released by the throw points 120 of the cam groove 121, said throw points lifting the lever B^9 intermittently for a sufficient distance to cause the nut or shoulder B^{22} to meet the lower end of the sleeve B^{23} of the stirrup and the carrier d^2 , and move said extension d^{18} to relieve the locking bar as stated from the clamping pressure exerted through the spring B^4 , so that if the controlling lever c^{21} is at that time held by the operator, he being desirous to start the wire-feeding mechanism into operation, the compressed spring 47^x may automatically expand, move the controlling lever and withdraw the locking bar from below the said extension, and such movement of said controlling lever will immediately move the releasing means for starting the wire-feeding mechanism and enable it to be started into operation, and at the same time the wire-cutting mechanism will be put into operation.

It will be understood that the compression of the spring B^4 , when the horn is locked in its depressed position, puts that spring in a condition to normally act, when released, to pull downwardly the rod d^6 having the connected rack or bar d^5 .

Whenever the pawl or engaging device of the carrier, coöperating with said rack or bar is disengaged therefrom, as it may be by any usual stop d^{10} , the horn may be moved upwardly by the spring B^4 , but if the descent of the carrier d^2 is arrested by the locking bar, then the pawl or engaging device is not thrown out of engagement with the rod or bar d^5 and the horn is kept depressed with the spring B^4 under compression, and said spring becomes effective to insure the firm clamping of the locking-bar by said extension for the greater part of each

cycle of operation of the machine. Whenever the locking bar is withdrawn, as herein provided for, the stirrup and carrier d^2 descend, and the full stroke of the rod B^{22} may be effective in raising the carrier, the spring B^{31} being effective to lower the carrier to the full extent of its stroke. The employment of the spring B^{31} , which may be compressed, as described, enables the carrier d^2 to remain at rest with its pawl in engagement with one or the other of the ratchet teeth of the rack or bar d^5 , that depending upon the thickness of the stock between the tip of the horn and the nose f when the wire feeding mechanism is thrown out of operation. The locking bar d^{20} is interposed between the extension d^{18} and the shoulder d^{12} only after the operator has removed his foot from the treadle 44, the releasing of said treadle enabling the depressing spring $\tilde{51}$ to assume the control of the controlling lever and move it in a direction to put said locking bar under said extension at a time when the carrier is in its most elevated position and the horn occupies its lowest position for feeding, said position varying according to the thickness of the stock then on the horn.

When the horn depressing mechanism is held, as described, in the position shown in Fig. 1, the spring B^4 is also compressed and pulls normally down on the rack or bar d^5 then coupled operatively with the carrier by the pawl or engaging device d , and said spring also by pulling down the carrier d^2 maintains the extension d^{18} firmly against the locking bar d^{20} and maintains the controlling lever c^{21} in its inoperative position.

Figs. 1, 6 and 9 show the lock and its mechanism with the parts of the machine in the position they will occupy when the wire-feeding mechanism is at rest, the horn down and the action of the wire-cutting mechanism suspended, the locking bar at such time occupying a position under the extension d^{18} , and it will be supposed that the wire carrying spindle A^{10} is being rotated rapidly by the belt on its pulley A^9 , and that the shafts B^{14} and d^{18} are being rotated with and from the said spindle, and also that the cams D^{17} and B^{13} are being rotated and that the heel 29, one of the operative instrumentalities of the wire cutting mechanism, stands in its dotted line position, Fig. 6, and that the stop 35 under the nut 40 holds the wire-feeding mechanism in its inoperative position.

The operator having applied a shoe to the horn then in its lowered position, puts his foot on the manually operated treadle or device 44, depressing the same and elevating the manually controlled device or rod 43 thus moving the block 48 thereon, see Fig. 1, away from the inner end of the locking device 60, which serves the purpose of lock-

ing the rod and treadle in the position in which it is put by the operator preparatory to starting the wire-feeding mechanism, said locking device under the action of its spring 62 immediately passing under said block 48, as shown in Fig. 3, where it stands always for a period of time sufficient to insert at least one fastening.

The elevation of the rod 43 compresses the spring 47^x, thus storing up energy in said spring so that on the next ascent of the rod B²² and its nut B²², following the compression of said spring 47^x by the movement of the treadle 44 and rod 43, the said nut 15 strikes the sleeve B²³ and lifts the stirrup B²⁴, sufficiently to lift and remove the extension d¹⁸ from the locking bar d²⁰. The stored up energy in the spring 47^x now acts to turn quickly the controlling lever c²¹ in 20 the direction of the arrow thereon, see Fig. 3, until the locking bar meets the stud 22^x to remove the locking bar from beneath the extension d¹⁸ that the carrier d² of the horn depressing mechanism may thereafter be reciprocated for its full stroke and enable the pawl or engaging device d to engage the teeth of the rack or bar d⁵ and depress the horn for feeding, said horn being depressed 25 for the same distance from the underside of the work of whatever thickness in order to enable the feed to take place.

As the controlling lever c²¹ is automatically actuated, as stated, by the spring 47^x, said lever elevates the rod 24, causing its wedge-shaped end 25, coöperating with the inclined hub 40^x, to immediately remove the stop 35 from its contact with the nut 40, thus releasing the wire-feeding mechanism and letting it assume its operative position, 30 this being done at such time with relation to the timing of the cam D¹⁷ that the roller or other stud D¹⁶ of the lever D¹⁴ of the wire-feeding mechanism shall contact with the face of said rapidly rotating cam or continuously moving actuator D¹⁷ at exactly 35 the proper point to insure the feeding of the wire for a length sufficient to meet the tip of the horn in the position it then occupies in contact with the stock, so that the first fastening inserted in the work after 40 starting the machine will always be of the full and proper length. At this time the arm 22^x of the hub 22 rises and carries with it the spring 55, so that said spring acting 45 on the collar 54 of the rod 26 turns the heel 29 from its dotted line position, Fig. 6, and full line position Fig. 8, into the dotted line position Fig. 8, the said heel in such position meeting a stop surface 70 of the lever C, 50 thus putting said heel into its working position. The spring 55, by its compression, keeps said heel firmly in position so that it is met by the toes C', C², of the cam B¹² in the rotation of said cam, which results in 55 moving the lever C sufficiently to operate

the wire-cutting mechanism and sever the wire close to the stock after the same has been inserted far enough into the stock to meet the tip of the horn, this operation being continued as long as the operator desires to insert fastenings in succession, and during this time the spring 55 will yield somewhat under the action of said toes upon the heel 29; and so also the spring 112 will yield, it effecting after each depression of 70 the lever C the elevation of said lever so as to keep it in such position that the heel may be acted upon by the toes so long as the operator desires to insert fastenings. The finger d¹⁶, connected with the carrier d², is 80 depressed while inserting each fastening, and at each descent of said finger its cam face 20 meets the roller 61 of the locking device 60 and withdraws the same from underneath the block 48 connected with the rod 43, 85 so that if the operator has previously taken his foot from the treadle 44, he being desirous of stopping the operation of the wire-feeding and other mechanisms, the block 48 of the rod 43 may descend behind the end of 90 the locking device, letting the head end of said rod 43, under the action of a depressing spring 51, meet the controlling lever c²¹ and turn the same in a direction opposite the arrow thereon to thus cause the locking bar 95 to again come into its position under the extension d¹⁸ when the stirrup and carrier are in their elevated positions. When the rod 43 is permitted to descend the end of the locking bar may be in contact with the vertical side of the extension d¹⁸, but said locking bar cannot get under said block until it is elevated, so while the controlling lever is maintained in its position, Fig. 4, the end of 100 arm 22^x of the split hub will also be kept in 105 its elevated position, and the spring 55 in such condition of the parts will yield to enable the toes C' and C² to meet the heel 29 and depress the rod 26.

Fig. 3 shows the controller bar in the position it will occupy as soon as the spring 47^x has been compressed to become the automatic mover for the controlling or starting lever c²¹, the locking device being represented as engaging the block 48, but Fig. 4 110 shows the controlling or starting lever c²¹ in the position in which it is put by the expansion of the spring 47^x, the locking bar being in its inoperative position and the wire-feeding mechanism and wire-cutting mechanism 115 being supposed to be in their operative positions. The lever c²¹ will remain in the position Fig. 4, and the insertion of fastenings will be continued as long as the operator retains his foot on the treadle 44 and keeps 120 the rod 43 elevated, but as soon as he removes his foot from the treadle, this being preparatory to putting the wire-feeding and wire-cutting mechanisms in their inoperative 125 positions and the putting of the locking 130

5 bar in position to arrest the descent of the carrier d^2 , the finger or wedge d^{16} connected with the carrier at the descent thereof following the release of the treadle by the operator, meets the roller or other stud 61 and withdraws the locking device 60 so that the depressing spring 51 is free to act and move the controlling lever c^{21} and with it move the locking bar toward the extension d^{18} , as 10 in Figs. 1 and 3, and in this movement of the controlling lever the wire-feeding mechanism will be locked in its inoperative position, and the heel 29 operative in the wire-cutting mechanism will be turned into its 15 inoperative position, as shown by dotted lines in Fig. 6, and the reciprocations of the stirrup and its carrier d^2 will be stopped, notwithstanding the rod B^{22} continues to operate through the sleeve of said stirrup, 20 and the horn will be stopped in its lowered position, as stated.

It will be seen that the operator may compress the spring 47^x for moving the controlling lever c^{21} at any time in the cycle of 25 movements of the continuously moving actuators for the groups of devices hereinbefore named, but said devices will not be put under the control of their actuators at the time of such manual operation but at the 30 proper time in the cycle of operations of the actuators to insure the proper action of the wire feeding and wire-cutting mechanism and the release of the horn.

The operator having compressed the 35 spring, as herein represented, by a manually controlled device, a rod moved by a lever, retains his foot upon the treadle for as long a period as he desires that the machine shall 40 continue to operate and insert fastenings, but when the machine is to be stopped the operator may remove his foot from the treadle, referred to, at any point in the cycle 45 of operations of the continuously moving actuators and thus release the controlling lever and put it under the control of another spring which at an exact time in the 50 cycle of operations of the continuously moving actuators will move said lever so that it, through suitable connections operated by it, 55 will arrest the further movement of the wire-feeding mechanism putting it in its inoperative position and stop the movement of the wire-cutting mechanism and lock the horn in lowered position that the stock may be readily removed therefrom.

The drawing, Fig. 1^a, shows an auxiliary feeding or gripping roller 72, which in practice will be toothed at its periphery to engage the threads of the wire. There is a roll 60 of this kind for each gripper b' , said rolls being contained in suitable pockets in said grippers and by their engagement with the threads of the wire they act as auxiliary feeding devices augmenting the efficiency of 65 the teeth of the grippers, the roller teeth and

gripper teeth coöperating together to feed the wire in a superior manner. These rollers act only when the sleeve F and grip carrier descend, they rolling over the wire when the said sleeve and gripper carrier rises. 70

Having described my invention, what I claim and desire to secure by Letters Patent is:—

1. In a machine for inserting fastenings, a horn, horn depressing mechanism, a controlling lever, a controlling rod coöperating therewith, means to move said rod, and a locking bar actuated by said lever to engage said horn depressing mechanism and maintain the horn in its lowered position. 75

2. In a machine for inserting fastenings, wire-feeding mechanism, a controlling lever operative in starting said wire-feeding mechanism, a controlling rod coöperating therewith and provided with a block; and means whereby said rod may be lifted; combined with a locking device to coöperate with said block and lock the controlling rod in position to insure the feeding of the wire. 85

3. In a machine for inserting fastenings, wire-feeding mechanism, a controlling lever containing a spring, means to lock said lever in its inoperative position, a manually controlled device acting to compress said spring, and a locking device to engage said manually controlled device and retain the spring in its compressed condition ready to operate said lever and start the wire-feeding mechanism when the locking means for said lever is released. 90

4. In a machine for inserting fastenings, a controlling lever, a manually controlled rod to move said lever, an arm connected with said lever, a cutter actuating lever, and a movable heel mounted thereon, combined with a rod operatively connected with said heel and extended loosely through said arm, and a spring surrounding said rod and sustained at one end by said arm. 105

5. In a machine for inserting fastenings, wire-feeding mechanism including a feed lever having a measuring device provided with a projection, said feed lever being instrumental in moving the wire-feeding mechanism, and a feed starting rod having a stop coacting with said projection to hold said feed lever in its inoperative position, combined with a controlling lever, connections between said controlling lever and said feed starting rod, a lock for locking said lever in its inoperative position, means for automatically releasing said lock, and manually-controlled means to insure the automatic movement of said controlling lever when released, that the feed starting rod may withdraw said stop from said projection. 110

6. In a machine of the class described, a slide rod having a feed stop, a spring to move said slide rod in one direction, and a feed lever having a measuring device pro- 125

vided with a projection, combined with a rod having a wedge, and means to actuate said rod to move the rod having the feed stop to withdraw said stop from under said 5 projection when it is desired that the feed lever shall be started.

7. In a machine of the class described, a horn, a lever connected therewith, a rod provided at one end with a bar, a carrier having 10 a device to engage said bar to move the same, a stirrup having a sleeve and attached to said carrier, a lever, and means to actuate the same constantly during the operation of the machine, combined with a rod connected 15 with said lever and extended through the sleeve of said stirrup, said rod having a projection to engage said sleeve and lift said carrier, and a spring surrounding said rod and bearing on said sleeve at each descent of 20 said rod.

8. In a machine of the class described, a horn, a lever connected therewith, a rod having a bar, a carrier having a stirrup and a connected device to engage and move said 25 bar, a lever, and means to actuate said lever constantly during the operation of the machine, combined with a rod and spring for 30 yieldingly connecting said lever with said stirrup, and means to arrest said carrier in its elevated position.

9. In a machine for inserting wire, a controlling lever, a connected locking bar, wire-feeding mechanism, a feed starting rod operatively connected with said controlling 35 lever, a horn, a connected bar, a carrier having a device to engage and move said bar, means to clamp said locking bar, a stirrup having a sleeve and connected with said carrier, a lever, means to actuate said lever 40 constantly, and a rod connected with said lever and extended loosely through said sleeve, combined with a spring carried by said rod and acting normally on said stirrup to depress said carrier, a projection on 45 said rod adapted to act upon said stirrup to lift said carrier at each ascent of said rod sufficiently to release said locking bar, and means for moving said controlling lever automatically when the action of the wire- 50 feeding mechanism is to be started.

10. In a machine for inserting wire, wire-feeding mechanism, wire-cutting mechanism, device to determine when said mechanisms may be actuated, a manually controlled rod 55 having a block, a locking device to engage said block and keep said rod locked in its elevated position, a controlling lever actuated by said rod, and means intermediate said lever and the devices to determine when said wire-feeding and wire-cutting mechanisms are to be operated whereby when said lever is moved the wire-feeding mechanism and the wire-cutting mechanism will be started.

65 11. In a machine of the class described, a

horn, a lever connected therewith, a rod having a bar, a carrier having a device to engage and lift said bar, a lever, and means to actuate said lever constantly during the operation of the machine, combined with a spring 70 and a rod loosely connecting said lever with said carrier, a controlling lever having a connected locking bar to arrest said carrier in its elevated position, a manually controlled device having a block, a locking device 75 and a spring to move it to engage said block, and a cam-shaped finger movable with said carrier and adapted to withdraw said locking device from its engagement with said block. 80

12. In a machine of the class described, a horn, a horn-depressing mechanism, a manually-controlled rod, devices intermediate said rod and said horn-depressing mechanism, wire-feeding mechanism, devices intermediate 85 said rod and said wire-feeding mechanism, and means for elevating said rod to insure the starting of the wire-feeding mechanism, combined with a block on said rod, a locking device to engage said block and prevent the descent of said rod after the operator releases said rod, and a device connected with said horn-depressing mechanism and actuating said locking device to release said rod at a predetermined time to permit the 90 horn to descend and effect the stopping of the wire-feeding mechanism. 95

13. A horn, a constantly actuated lever, connections between said lever and horn having provision to slide one on the other, combined with a locking bar, and means to operate it at the desired time to place said bar between the connections of said lever and horn to arrest the tip of the horn in its lowered position and yet enable the lever 105 referred to to be actuated.

14. In a machine for inserting wire, a horn, means to depress the same, including a vertically movable carrier having locking bar clamping means and a constantly moving rod, wire feeding mechanism, wire cutting mechanism, a manually controlled rod having a block, a locking device to engage said block and keep said rod locked in its elevated position, a controlling lever actuated by said manually controlled rod and having a connected locking bar, and devices connected with and actuated by said controlling lever in its movement in one direction to enable the wire feeding mechanism 110 and the wire cutting mechanism to be started while said rod is in its elevated position, means to withdraw said locking device to permit the descent of said manually controlled rod that said controlling lever may 115 move in the opposite direction and cause its bar to coact with the clamping device of said carrier and retain said lever in its inoperative position to effect the suspension of the operation of the wire feeding and wire 120 125 130

cutting mechanisms said locking-bar arresting the horn in its lowered position in order that the work may be removed.

15. In a machine of the class described, a controlling lever having a seat and containing a spring, a locking bar attached to said lever, a carrier with which it cooperates, a headed rod adapted to act on said spring to compress the same preparatory to turning 10 said controlling lever to withdraw said locking bar from said carrier, the head of said rod when the latter is depressed turning the controlling lever in a direction to force the locking bar into position to arrest the movement of said carrier.

16. In a machine of the class described, a horn or stock-support, horn depressing mechanism having a locking-bar clamping portion, a controlling lever, a connected 20 locking-bar, a support for said locking-bar, and means to turn said lever and force said locking-bar under said clamping portion that said bar may be held between said clamping portion and support to lock the 25 horn down whenever the latter is to be held depressed for the removal of the work therefrom.

17. In a machine for inserting fastenings formed from wire, a continuously moving 30 actuator, wire-cutting mechanism including a lever having movably mounted upon it a block provided with a heel, said block having a connected rod which normally puts said heel in its inoperative position with relation to its continuously moving actuator, a 35 spring surrounding said rod, a controlling lever, means to automatically move said controlling lever at a predetermined time to turn said heel into its operative position 40 that the wire-cutting mechanism may be started into operation.

18. Wire-feeding mechanism, a continuously moving actuator, a stop to hold said wire-feeding mechanism in its inoperative 45 position, an automatically operated controlling lever, and means comprising a wedge moved by said lever to withdraw said stop and release the wire-feeding mechanism and put it under the control of its actuator to 50 feed the wire.

19. In a machine for inserting fastenings, a horn, means operating continuously to lower the horn at intervals, a controlling lever having a connected locking bar, a 55 spring carried by said controlling lever, a manually-controlled device for compressing said spring, said device having a block and a second spring for moving said device in a second spring for moving said device in an opposite direction that it may move said 60 controlling lever automatically at an exact predetermined time in the cycle of operation of the machine to withdraw said bar and release the horn that it may rise, meet and caliper the stock.

20. Wire feeding mechanism, wire cutting

mechanism, a stop to suspend the operation of said wire feeding mechanism, continuously moving actuators for said mechanisms, a heel movable with relation to said wire cutting mechanism, a controlling lever, connections between said lever and said stop, and between said lever and said heel, means to lock and restrain the movement of said lever while the wire-feeding mechanism and wire-cutting mechanism are to occupy their 75 inoperative position, and means for turning said lever automatically when the means for locking the same has been moved to release said lever that the latter may through said connections insure the starting of said 80 wire-feeding and wire-cutting mechanisms.

21. Wire feeding mechanism including a lever, wire cutting mechanism presenting a movable heel, continuously operating actuators for said wire feeding mechanism and 85 said wire cutting mechanism, a rod having a stop to hold said wire feeding mechanism in its inoperative position, a controlling lever, and a manually controlled device to insure the movement of said lever when the 90 wire feeding mechanism and the wire cutting mechanism are to be put into operation, and means intermediate said controlling lever and said wire-feeding mechanism and wire-cutting mechanism and moved by said 95 lever to cause the wire feeding mechanism to be put under the control of its actuator and also to maintain the heel of the wire cutting mechanism yieldingly in its operative relation to its actuator.

22. A horn, a ratchet bar operatively connected therewith, a carrier to engage said ratchet bar when the horn is to be depressed, a spring acting normally to elevate said 105 horn when said ratchet bar is disengaged from said carrier, means to raise and lower said carrier, a locking-bar and means to interpose said bar between said carrier and a fixed part of the machine when said carrier is lifted to thereby lock the horn in its low- 110 position.

23. In a machine of the class described, a carrier, a horn, a connected ratchet bar, a continuously moving lever, a rod carried thereby and engaging loosely said carrier, a 115 projection and a spring carried by said rod and coacting with said carrier, said rod lifting said carrier, and said rod and spring depressing the same.

24. In a machine for inserting fastenings, 120 a carrier provided with an extension, means acting positively to lift said carrier and yieldingly to depress said carrier, a horn having a connected bar, a spring acting normally to elevate said horn, means to effect 125 the firm engagement of said carrier and bar when said horn is to be depressed, said means sliding freely over said bar when said horn is acting to clamp the stock, combined with a locking-bar, and means to in- 13

- terpose the same in the path of the extension of said carrier thereby to retain the horn in a lowered position for the removal or application of the stock.
- 5 25. In a machine for inserting fastenings, a horn, a carrier unobstructed in its movements in lowering the horn during the operation of inserting fastenings, a continuously moving actuator, a lever operated continuously by said actuator, a shouldered rod connected with said lever to lift said carrier, a spring interposed between said lever and said carrier to depress the latter, a locking bar to arrest the descent of said carrier, and 10 means to interpose said locking bar in the path of descent of said carrier when the horn is to be retained in its depressed position, the said spring at such time yielding.
26. In a machine for inserting metallic fastenings, a horn, a continuously moving actuator, a horn depressing lever moved continuously by said actuator, a rack or bar operatively joined with the horn, a carrier having an engaging device to engage said 15 rack or bar on the upstroke of the carrier to depress the horn, and a loose connection between the continuously operated lever and the carrier whereby the descent of the carrier may be arrested without arresting the movement of the continuously moving actuator and the lever operated continuously thereby.
27. In a machine for inserting wire, wire-feeding mechanism, wire-cutting mechanism, a horn to sustain the stock, means for raising and lowering said horn, a manually-controlled rod having an attached block, a locking device to engage said block to keep 20 said rod locked in its elevated position, a spring to depress said rod when said locking device is disengaged from said block, a controlling lever, a connected locking bar, and a spring in said controlling lever, combined with devices connecting one end of said controlling lever with said wire-feeding and wire-cutting mechanisms, whereby when said lever is moved in one direction by the spring within the same, the wire-feeding mechanism and the wire-cutting mechanism may be 25 started and the horn be unlocked, and means for moving said locking device to effect the release of said manually-controlled rod that said controlling lever may be turned by the spring arranged to depress said rod, to thereby stop the operation of the wire-cutting mechanism and leave the horn in its depressed position.
28. In a machine for inserting wire, a horn, wire feeding mechanism, a controlling lever having a spring adapted to be compressed to move said lever automatically at a later period, a connected locking bar, a carrier instrumental in depressing the horn, and adapted to clamp said locking bar and

65 maintain said controlling lever in its inoperative position while the wire feeding mechanism is in its inoperative position and the horn is depressed for the removal of work, a manually controlled rod to compress said spring, a block carried by said rod, a 70 locking device to engage said block and maintain said spring compressed while said locking bar is clamped, and means to lift said carrier to release said locking bar that said compressed spring may automatically 75 turn said controlling lever and start the wire feeding mechanism, and means actuated by said lever to start the wire-cutting mechanism to sever the wire.

29. In a machine for inserting fastenings, 80 a horn, wire feeding mechanism, a controlling lever, controlling mechanism between said lever and said wire feeding mechanism, a locking bar operated by said lever, a rod under the control of the operator, a 85 spring to move said rod and actuate said lever, mechanism for lowering the horn, and means to put said locking bar in position to maintain the horn in its lowered position and suspend the operation of the wire feed- 90 ing mechanism.

30. A work support, lowering means therefore including a carrier and a yielding actuator operatively joined therewith to effect the lowering of the work support to allow the 95 work to be fed, a continuously operating cam for moving said yielding actuator, and means for locking the carrier of the lowering means to maintain the work support in lowered position for the removal or application of stock while said actuator continues in operation.

31. In a machine for inserting fastenings, a manually controlled rod, a horn, a spring to elevate the horn, wire cutting mechanism, 105 and wire feeding mechanism, combined with a controlling lever containing a spring, a locking bar connected therewith, horn depressing mechanism having means to engage said bar and lock the controlling lever in its 110 inoperative position while the operation of the wire feeding and wire cutting mechanisms is suspended and while the horn is depressed, and means to actuate said horn depressing mechanism to release said locking bar that the spring coacting with said horn may elevate the latter to clamp the stock, and that the wire feeding and wire cutting mechanisms may be placed automatically 115 under the control of their actuators. 120

32. In a machine for inserting fastenings, a horn, horn depressing mechanism, wire feeding mechanism, an actuator for said wire feeding mechanism, means for stopping the operation of said wire feeding mechanism while its actuator continues in operation and means released by a movement of the horn-depressing mechanism for restor-

ing said wire-feeding mechanism to its actuator.

33. A work support, a device to effect the lowering of the work support for the removal or application of work, an actuator, mechanism constantly operated by said actuator to operate said device, and means to stop the movement of said lowering device to leave the work in its lowered position, while said mechanism continues in operation.

34. Wire feeding mechanism, a continuously moving actuator, a stop, a spring to move said stop when permitted into position to maintain said wire feeding mechanism in its inoperative position, a horn, a measuring rod connected therewith and coacting with said wire feeding mechanism to position the same according to variations in thickness of the stock, and an automatically operated device to withdraw said stop to release said wire feeding mechanism to permit the stock to be calipered before said wire feeding mechanism meets its actuator to be started to feed the wire.

35. In a machine of the class described, a carrier, a horn, a connected ratchet bar, a continuously moving lever, a rod carried thereby and engaging loosely said carrier, a projection and a spring carried by said rod and coacting with said carrier, said rod lifting said carrier, and said rod and spring depressing the same, and means to lock said carrier in its elevated position to retain the horn depressed for the removal of stock.

36. In a machine for inserting fastenings, a horn, a rack connected therewith, a carrier having a connected extension, an engaging device mounted on said carrier to engage said rack, means to raise said carrier to depress the horn, a controlling lever, a locking bar, and means to turn said lever to force said bar toward said carrier when in its elevated position that said bar may be thrust under said extension and lock the carrier in its elevated position with the horn depressed for the removal of the work.

37. In a machine of the class described, a controlling lever containing a spring, a connected locking bar, means to temporarily clamp said locking bar to restrain the movement of said controlling lever, a manually controlled device to compress said spring while said locking bar is held clamped, a locking device to retain said manually controlled device in position to hold said spring compressed that it may act to turn said controlling lever when said clamp releases the locking bar.

38. In a machine of the class described, wire feeding mechanism, a controlling lever, means connected therewith to suspend the operation of the wire feeding mechanism when said controlling lever occupies one position, and to permit said wire feeding mechanism to be started when said control-

ling lever occupies its other position, a carrier, means for actuating the same and a locking bar connected with said controlling lever and adapted to be locked by the carrier when in its elevated position to prevent the starting of the wire feeding mechanism except at just the proper moment, and locked when the carrier is down, to prevent the movement of said lever in a direction to suspend the operation of the wire feeding mechanism.

39. In a machine of the class described, a controlling lever containing a spring, a connected locking bar, means to temporarily clamp said locking bar to restrain the movement of said controlling lever, a manually controlled device to compress said spring while said locking bar is held clamped, a locking device to retain said manually controlled device in position to hold said spring compressed that it may act to turn said controlling lever when said clamp releases the locking bar, and a stop to limit the extent of movement of said locking bar and consequently of said controlling lever under the action of its spring.

40. In a machine for inserting fastenings, a horn, horn depressing mechanism including a continuously moving rod having a shoulder, a controlling lever having a spring and a connected locking-bar adapted to be held fixedly by the horn-depressing mechanism when the horn occupies its depressed position, a feed lever forming part of wire-feeding mechanism, it occupying its inoperative position while the horn is depressed and said bar is locked, manually-controlled means to store up energy in the spring of said controlling lever that said lever may be moved when the locking-bar is released through the elevation of the horn-depressing mechanism, said movement of the horn-depressing mechanism in lowering the horn releasing the locking-bar automatically and allowing said controlling lever to start the wire-feeding mechanism.

41. In a machine of the class described, a horn or stock support, horn-depressing mechanism having a locking-bar clamping portion, a controlling lever, a connected locking-bar, a support for said locking-bar, means to turn said lever and force said locking-bar under said clamping portion that said bar may be held between said clamp and support to lock the horn down whenever the latter is to be held depressed for the removal of the work therefrom, and a manually-controlled device having a block, and a locking device to engage said block.

42. In a machine of the class described, a horn or stock support, horn-depressing mechanism having a locking-bar clamping portion, a controlling lever, a connected locking-bar, a support for said locking-bar, a spring carried by a manually controlled de-

vice to turn said lever and force said locking-bar under said clamping portion that said bar may be held between said clamp and support to lock the horn down whenever the latter is to be held depressed for the removal of the work therefrom, a manually-controlled device having a block, a locking-device to engage said block, and means connected with said horn-depressing mechanism to withdraw said locking device when the horn-depressing mechanism is depressed and the horn correspondingly raised.

43. In a machine of the class described, a manually-controlled device having a block, a horn, a carrier for depressing said horn, a controlling lever having a connected bar adapted to engage and lock said carrier in its nearly elevated position with the horn nearly depressed to its full limit, a spring in said controlling lever adapted to be compressed by said manually-controlled device while said locking bar is held in its locked position by said carrier, means for locking said manually-controlled device in position after said spring has been compressed, that said spring may subsequently act and withdraw said locking bar at the final upward movement of said carrier, to thereby unlock the horn that it may rise to caliper the stock and start the wire-feeding and wire-cutting mechanisms, and means connected

with said carrier to unlock, in the descent of the carrier, said manually-controlled device that it may, after said wire-feeding mechanism and said wire-cutting mechanism have been operated, move said controlling lever at the next upward movement of said carrier to again place its locking bar in position to maintain the horn depressed and render the wire-feeding and wire-cutting mechanisms again inoperative.

44. In a machine of the class described, a rod having a stop and instrumental in starting into operation wire-feeding mechanism, an arm having a heel and instrumental in causing wire-cutting mechanism to be operated, combined with a controlling lever, a rod connected with said lever, and sustaining a wedge for moving the rod having said stop into its inoperative position, an arm carried by the rod having the wedge, and means moved by said arm to control the position of said arm having said heel, as and for the purpose described.

In testimony whereof, I have signed my name to this specification, in the presence of two subscribing witnesses.

ORRELL ASHTON.
